UNITED STATES PATENT OFFICE.

REZEAU B. BROWN, OF MILWAUKEE, WISCONSIN, ASSIGNOR TO RITER-CONLEY MANUFACTURING COMPANY, OF PITTSBURGH, PENNSYLVANIA, A CORPORATION OF NEW JERSEY.

REGENERATIVE-RETORT BENCH.

1,094,523.

Specification of Letters Patent. Patented Apr. 28, 1914.

Application filed March 28, 1903. Serial No. 149,067.

To all whom it may concern:

Be it known that I, REZEAU B. Brown, a citizen of the United States, residing at Milwaukee, in the county of Milwaukee and State of Wisconsin, have invented a new and useful Improvement in Regenerative-Retort Benches, of which improvement the following is a specification.

My invention relates to improvements in gas furnaces and particularly in the construction of the passages of ducts through which the air passes from the exterior to the combustion chamber and passages through which the waste products of combustion pass from the combustion chamber to the exterior.

The objects of my invention are to produce a construction of air passages which can be varied or changed so as to cause the air to circulate more or less circuitously in its passage to the combustion chamber and thus, by being in contact with the heated passages a longer or shorter period, vary the temperature of the air introduced into the combustion chamber dependent upon existing conditions and requirements.

Another object of my invention is to so construct said air and waste product passages, independently of the furnace and bench walls so that the expansion and contraction of the furnace and bench walls will not seriously affect the same.

A further object of my invention is to so construct said air passages as to enable the change and variation therein, and the cleaning thereof, to be readily effected from the front without disturbing the furnace and bench walls; and to accomplish these several objects my invention consists in the novel construction and arrangement of parts hereinafter more specifically described, reference being had to the accompanying drawings, in which—

Figure 1 indicates a front elevation, in section, of my improvement. Fig. 2 indicates a longitudinal section on line $x-x$ of Fig. 1. Fig. 3, a section on line $y-y$ of Fig. 1.

Like reference characters indicate like parts wherever they occur.

Referring to said drawings, 1-1 are the bench walls of the gas retorts 2, 2.

3 is the furnace for the production of initial combustion having a grate 4, of any usual or desired construction, side walls 5-5 and arch 6. The said arch is provided

with an opening or nostrils 7, for the purpose of admitting the products of combustion from the initial furnace 3 to the combustion chamber 8 above which the retorts, 2, are located longitudinally of the same.

Ports 9 for the exit of the waste products of combustion, and ports 10 for the admission of air to the combustion chamber are located between the walls of the furnace and the walls of the bench. The said ports or flues 9 communicate with the combustion chamber by means of the ports 11-12-13, and the ports 10 communicate with the combustion chamber by means of ports 14-15. The said ports 9 are formed between the parallel and vertically disposed tile 16, and the supports 17, which are transversely disposed at intervals between the walls of the furnace and those of the bench but are not connected to the furnace or bench walls in any manner whatsoever. The lower edge or bottom of the said supports, near the ends thereof, are provided with grooves, a, a , into which the tongues b, b , formed in the upper edge of the tile, respectively, project, and the tops of said supports are provided with tongues c, c , which are inserted in the grooves d, d , formed in the lower edge of each of said tiles 16, thus forming a rectangular port or opening, 9, which may be made higher if desired by mounting two of said tiles vertically between the supports. On the sides of said tile adjacent to the furnace and bench walls, respectively, are formed spaces, which are subdivided into narrow air ducts 10, 10, formed between said walls and tile 16 and the adjustable tile or baffles 18, which rest loosely upon the projecting ends of the supports, and are capable of being positioned at any desired place in said spaces so as to change, modify and control the circuit or course of the incoming air, for the purpose of making its course to the combustion chamber more or less circuitous and thus regulating its period of contact with the walls of said ducts 10-10 which are heated by radiation from the furnace walls and from the highly heated products of combustion which pass through the ports 9-9 to the stack.

Some of the advantages of this construction are, first, the said air and waste product passages being constructed between the furnace and retort bench walls, the highest possible preheating of the incoming air is at

tained; and being constructed independently of said walls, the expansion and contraction therof does not affect said passages, second, the baffles or tile 18 constituting the top or 5 upper wall of the air passages not being connected in any manner whatsoever to the bench and furnace walls, are not affected by the expansion and contraction of the same, and being adjustable, the circuit of the air 10 can be changed, if desired, and finally, whatever adjustment or change in the disposition of said baffles may be required and the cleaning of said passages can be accomplished through the openings in the front and rear 15 walls.

I claim as my invention and desire to secure by Letters Patent:

1. In a gas furnace, the combination with a combustion chamber, gas retort bench, and 20 separated combustion chamber and retort bench walls, of flues or ducts located between the walls of the combustion chamber and retort bench and separated therefrom by spaces constituting additional flues, and 25 adjustable baffles located in said spaces and independent of said walls.

2. In a gas furnace, the combination with a combustion chamber, gas retort bench, and separated combustion chamber and retort 30 bench walls, of flues or ducts located between the walls of the combustion chamber and retort bench and separated therefrom by spaces constituting additional flues, and baffles located in said spaces and adjust- 35 ably supported by the flues or ducts and independent of said walls.

3. In a gas furnace, the combination with a combustion chamber, gas retort bench, and separated combustion chamber and re- 40 tort bench walls, of transverse supports arranged at intervals between the walls aforesaid and independent thereof, tile resting on said supports in superposed relation, thereby forming inner and outer flues 45 or ducts, and adjustable baffles independent of the walls resting on the transverse supports.

4. In a gas furnace, the combination with

a combustion chamber, gas retort bench, and separated combustion chamber and retort 50 bench walls, of transverse supports ar- ranged at intervals between the walls aforesaid and independent of said walls, tile resting on said supports in superposed rela- 55 tion, thereby forming inner and outer flues or ducts, and adjustable baffles resting on the ends of the transverse supports and located between the tile and the walls aforesaid and independent of said walls.

5. In a gas furnace, the combination with 60 a combustion chamber, gas retort bench, and separated combustion chamber and retort bench walls, of flues or ducts removably lo- 65 cated between the walls of the combustion chamber and retort bench and supported in- dependently of the walls aforesaid and sepa- 70 rated therefrom by spaces constituting addi- tional flues and adjustable baffles slidably mounted in said spaces and independent of said walls and said first named flue.

6. In a gas furnace, the combination with 75 a combustion chamber, gas retort bench, and separated combustion chamber and retort bench walls, of transverse supports remov- ably arranged at intervals between the walls aforesaid but independent thereof, tile rest- 80 ing on said supports in superposed relation, thereby forming inner and outer flues or ducts, and adjustable baffles slidably mounted on the ends of the supports and located between the tile and the walls aforesaid, and independent of said walls.

7. In a gas furnace, a recuperator con- 85 structed and supported entirely independent of the walls on either side of it so as to be entirely removable without interference with any part of the furnace, and sliding baffles supported by said recuperator en- tirely independent of the furnace walls.

In testimony whereof I have hereunto 90 signed my name in the presence of two sub- scribing witnesses.

REZEAU B. BROWN.
